UNITED STATES PATENT OFFICE.

FREDERICK A. HART, OF JERSEY CITY, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,190,287.

Specification of Letters Patent.

Patented July 11, 1916.

Application filed August 9, 1911, Serial No. 643,108. Renewed May 27, 1916. Serial No. 100,188.

To all whom it may concern:

Be it known that I, FREDERICK A. HART, a citizen of the United States, residing in Jersey City, in the county of Hudson and State of New Jersey, have invented certain new and useful Improvements in Combined Type-Writing and Computing Machines, of which the following is a specification.

This invention relates to combined type-writing and computing machines, in which dial wheels or devices are returnable to zero by the use of a special key or mechanism.

One of the objects of the present improvements is to provide improved means for indicating upon the work sheet, the fact that the dial wheels have been turned to zero before the beginning of the computation on said sheet.

In carrying out the invention, I provide in the typewriter a special type, and this is normally locked against operation, and is preferably unprovided with a key. A spring, however, tends constantly to operate said special type, but this spring is restrained by means of a trip, the trip also serving to lock the type against manual actuation. Upon the depression of the zero key, the trip is released, and the spring throws the type up to print on the work sheet. During the ensuing operation of the computing mechanism, that is, during the actuation of the usual general operator, the type bar and connected parts are restored to normal positions.

Another feature of the invention relates to means controlled by the zero key for restoring to normal positions, any pins that may have been set at the time the zero key is operated; the pins referred to being employed for determining the extent of rotation of the dial wheels in the usual manner.

Other features and advantages will hereinafter appear.

In the accompanying drawings, Figure 1 is a part sectional side elevation of the combined typewriter and adding machine of the Underwood-Hanson type; showing the parts in normal positions. Fig. 2 is a perspective view of portions of the mechanism which control the special type in the typewriter; the parts being in normal positions. Fig. 3 is a rear view of the zero and error keys, showing the connection whereby the zero key operates the error mechanism;

while the error key can be operated independently of the zero key. Fig. 4 is a sectional side elevation of certain portions of the mechanism seen at the lower part of Fig. 1; but showing the zero key depressed, and the type-operating parts as having been operated. Fig. 5 is a plan of the dial wheels and tens-carrying mechanism. Fig. 6 is a sectional side elevation of the same. Fig. 7 is a sectional side elevation of the zero-setting arbor whereon the dial wheels are mounted, and the driving connections for said arbor. Fig. 8 is a view similar to Fig. 6, but illustrating the tens-carrying operation. Fig. 9 is a perspective view of the arbor and disk thereon seen at Fig. 7. Fig. 10 is an enlarged side elevation of a dial wheel and its connections. Fig. 11 is a sectional view of the devices seen at Fig. 10.

Numeral keys 1 and alphabet keys 2 are mounted upon levers 3 connected by bell cranks 4 to type bars 5, which strike rearwardly against a platen 6, the latter mounted on a carriage 7 and controlled by the usual letter-feeding mechanism, comprising a universal bar 8 engaged by the type bars.

Each numeral key has a stem 9 to depress one of a series of arms 10 upon rock shafts 11, which form parts of linkages 12, the latter having members 13 to engage and depress any of a series of pins 14 upon any of a series of bars 15, the latter having at their forward ends racks 16 to engage pinions 17, each connected by a pawl and ratchet to a dial wheel 18.

The position of the carriage 7 determines which of the rack bars 15 shall be elevated at the time that any key 1 is depressed, and hence determines which rack bar shall have one of its pins 14 projected below the same. The selection is effected by means of a dog 19 upon the carriage, having a beveled tooth 20 to engage the end of a jack 21 pivoted at 22, whose rear end 23 pushes down one of a series of rods 24 to vibrate one of a set of levers 25, the latter connected by linkages 26 to the rear ends of said rack bars 15, so that the latter are raised in succession as the typewriter carriage 7 feeds along. Upon the release of the key 1 from pressure, the rack bar 15 drops, and its projected pin 105 stands below the nest of rack bars.

After the keys 1 have been manipulated to write the number which is to be added, a

handle 27 is pulled forwardly, for the purpose of adding on the dial wheels 18 the number which is determined by the projected pins 14. This handle 27 is provided upon a crank 28 projected from a rock shaft 29 having at its ends segments 30 meshing with pinions 31, the latter meshing with racks 32, one provided upon each side of the machine, and connecting by bars 50, 52; 10 said racks 32 and bars 50, 52, forming a general operator; bars 50 being provided upon arms 33 which are connected to the sliding racks 32. The bar 50 is caused by the handle 27 to move horizontally forward 15 and pick up the rack bars 15 by means of the projected pins 14, so that the strokes of the several racks, and hence of their associated dial wheels, depend upon which pins in the several racks were depressed. The 20 sliding racks 32 are mounted in suitable guides upon the base, and rigidly connected by the bars 50, 52, both of the latter just beneath the dial-wheel rack bars 15. Upon the return stroke of the handle 27, the cross 25 bar 52 of the general operator engages shoulders 58 formed upon the under sides of the rack bars 15, and returns them to normal rear positions. The general operator also performs the function of restoring 30 all of the pins 14 which have been depressed. This is effected by means of a plate 59, which is mounted by ears 60 upon bell cranks 61, 62, the latter connected by a link 63; the plate being lifted by the general operator from the position at Fig. 1 to the 35 position at Fig. 4, in a manner explained in my pending application No. 466,836, filed December 10, 1908.

When the racks 16 are being returned 40 rearwardly by the bar 52 of the general operator, the individual pinions 17 turn idly, the latter having pawl devices 64 to engage with ratchet wheels 65 fixed inside of the dial wheels 18.

45 The dial wheels are held steady by spring detents 66, which engage gears 67 fixed on respective computing wheels, said gears 67 serving also as tens-carrying gears. The tens-carrying operation is initiated by 50 special teeth 68, one of which is fixed upon each of the dial wheels 18, in position to engage and operate, once in each revolution of the wheel 18, an adjacent tens-carrying pinion 69, the latter provided with a three-toothed gear 70 in position to mesh with and turn the gear 67 fixed on the computing wheel 18 of next higher denomination.

Although the tens-carrying operation depends upon the actuation of a pinion 69 by 60 the tooth 68 upon the dial wheel 18, still such tooth merely initiates the tens-carrying operation, the latter being completed by means of one of a series of power-driven assisting segments 77.

65 There is one segment 77 for each of the

computing wheels except the units wheel; and these segments are fixed upon a transverse horizontal shaft 78 which has at one end a pinion 79, the latter meshing with an idle pinion 80, which in turn meshes with 70 the teeth 53 on the left-hand slide 51 of the general operator, so that the pinion 79 is rotated forwardly and backwardly about a complete revolution at each cycle of movements of said general operator. The tens-carrying segments, however, are intended to 75 rotate only in one direction; and hence the shaft 78 on which they are fixed is connected by a ball or other clutch 81 with said pinion 79, so that the rotation of the pinion during 80 the advance of the operator is an idle one; the segment shaft 78 being turned only during the return stroke of the operator. In other words, during the forward stroke of the general operator, the teeth 68 on certain 85 of the computing wheels 18 operate to set the tens-carrying pinions 69, and during the back stroke of the operator, the segments 77 engage the pinions 69 and complete the tens-carrying operations by giving one-tenth of 90 a revolution each to the corresponding computing wheels 18. The tooth 68 on each wheel 18 imparts to the tens-carrying pinion 69 one-ninth of a revolution; there being nine teeth on said pinion; and each segment 95 77 is intended to turn its pinion two-ninths of a revolution; each pinion being thus turned one-third of a revolution in all, in order to rotate the gear 67 and the next wheel 18 one-tenth of a revolution.

Every third tooth on each tens-carrying pinion 69 is cut away, a portion 82 being left, however, sufficient to be engaged by a spring detent 83; the teeth being cut away in this manner so that the tens-carrying segments 77 may swing idly past the tens-carrying pinions when the latter are idle; the gap between the teeth adjacent to the cut-away tooth being sufficient to permit the free movement of segment 77. The tooth 105 68 on any computing wheel 18, by moving the tens-carrying pinion 69 one-ninth of a revolution, turns said pinion into position for engagement by its associated segment 77 upon the next return movement of the 110 general operator; whereby said pinion is advanced an additional two-ninths, and the wheel 18 of next higher denomination is turned one-tenth of a revolution. The segments 77 are arranged in spiral order on the 115 shaft 78, so that tens-carrying may proceed from low to high denominations throughout the gang of computing wheels during a single return stroke of the general operator, whereby all the wheels may be turned from 120 "9" to "0" progressively during said operator stroke.

In order to return the computing wheels to zero, a key 85 is depressed, and its stem depresses the front end of a lever 86, the 125

rear end whereof is provided with a wrist 87, which takes under and lifts the rear end of a special rack 88, which is similar to the racks 16, but is provided with only one settable pin 88^a similar to pins 14. Said pin 88^a encounters a fixed abutment 88^b, and hence stops before the upward movement of the rack 88 is completed, or in other words, the pin is forced to project below the rack, 5 by the upward movement of the latter. Upon them pulling forward the handle 27, the cross bar 50 of the general operator is advanced to engage said projecting pin 88^a and carry forward the special zero rack 88, 10 the forward end of which has teeth to mesh with a pinion 89, which has a ball-clutch connection to a disk 90, the latter being fixed to an arbor 91 upon which all of the computing wheels 18 are loosely mounted. 15 This arbor, which is given a full revolution by the general operator at the forward stroke of the handle 27, (since pin 88^a is placed one step to the rear of the "9" pins 14) has a clutch connection with every one 20 of the computing wheels 18, so as to bring the units wheel to zero point, and the remaining wheels to such positions that they all show "9" at the sight opening. The arbor 91 turns a full revolution; but all except the units clutch are set to such 25 positions as to be capable of giving their computing wheels each only nine-tenths of a revolution. The units wheel 18, in thus being turned to the zero position, effects by 30 means of its tooth 68, a ninth of a revolution of its associated tens-carrying pinion 69, thus turning the latter to an abnormal position, in which it is capable of being rotated by its associated segment 77 upon the 35 return stroke of the general operator, as already explained. Said segment of course turns not only the tens-carrying pinion, but also the next higher computing wheel, and the tooth 68 upon the latter effects a partial 40 revolution of the associated tens-carrying pinion 69, thus bringing the latter to position to be actuated by the next segment, as the return movement of the general operator continues. This second tens-carrying wheel, 45 turns the hundreds computing wheel to zero, and incidentally advancing the associated tens-carrying wheel, and so on, tens being carried from wheel to wheel throughout the series during the return stroke of the operator, so that at the conclusion of said return stroke all the wheels stand at zero. 50

The arbor 91 is arranged to be capable of turning all of the wheels except the units wheel only nine-tenths of a revolution, so 55 that the tens-carrying mechanism, when it operates, will simply complete the turning of the wheels to zero. It will be seen that said arbor 91 is connected to said computing wheels by spring-pressed balls 92, engaging 60 suitable cutaways 93 formed in the comput-

ing wheels; the units ball being one-tenth of a revolution in advance of the remaining balls, for the purpose set forth. A detent 94, engaging a notch 95 in the disk 90, holds the latter and arbor 91 in normal position. 70

If an error is made, the operator presses an error key 100, the stem of which has an arm 101, to which is attached one end of a draw-spring 102, the upper end of said spring connected to a lever 103 having a projection 104 to rest upon the top of a trip 105. A wrist 106 on the descending arm 101 presses said trip aside to the Fig. 4 position, and allows the tension-spring 102 75 to pull down said lever. The rear end of the lever rises and engages a wrist 107 on one of the bell-cranks 62, and thereby lifts the universal pin-restoring plate or tablet 59, to return to normal positions any pins 80 14, 88^a or other pins that may have been set. When the error key is released, a spring 108 returns it to normal position. An ear 108^a on the plate 59 restores the pin 88^a on the "zero" rack 88. 85

A spring 110 is connected to a lever 111 similar to the key lever 3, but preferably unprovided with any key; said lever 111 connected by a bell crank 4 with a type bar 112, having thereon a single type 113 which 90 may resemble the letter "C." This spring 110 tends normally to swing said type bar 112 up to print, it being connected thereto by a swinging frame 116, and a link 117 connected to the forward end of the lever 111. The frame 116 includes a rock shaft 128 and arms 114 and 115 secured thereto. The frame 116 is normally restrained by a pendent device 118 pivoted at 119 on the arm 114, and having near its lower end a projecting pin 120 which rests upon a shoulder 121 fixed upon a horizontal shaft 122 which forms the fulcrum of lever 86. 95

When the zero key 85 is depressed, as already explained, the lug 121 is swung forwardly to release the pin 120 and permit the spring 110 to pull down the arms 114, 115, the link 117, the lever 111, and throw the type bar 112 upwardly and rearwardly against the platen, so that the type 113 100 prints on the work sheet. This type is a special type substantially different from the ordinary "C," and different from all of the remaining types in the machine, and it cannot be operated at the will of the operator 105 by depressing the lever 111 because the latter is locked against movement by the pin 120 and lug 121. The imprint of the type 113 on the work sheet therefore indicates 110 that the machine has been cleared, or that the adding wheels have been returned to zero. 115

During the reciprocation of the handle 27 and of the general operator 32, which ensues upon the depression of the zero key 85, the 120 125

type bar 112 is automatically restored to normal position. This is effected by the shaft 78, upon which is mounted a cam 123, preferably a gravity cam having an abrupt dip therein, to take under a wrist 124 projecting from the arm 114 (the latter rigidly connected to arm 115 by means of the hub or hollow shaft 128, Fig. 2). This cam lifts said arms, thereby returning the type bar 10 to normal position, and lifting the device 118 until the pin 120 thereon is snapped, by means of a spring 129, over the end of the lug or arm 121. This occurs before the shaft 78 comes to rest. During the final portion 15 of the motion of the shaft 78, the cam 123 continues to turn until it is entirely out of engagement with the wrist 124, so as not to obstruct the subsequent downward movement of the latter. As will be seen in Fig. 20 2, this shaft and the cam thereon will be locked in its normal home position by a detent 150 which engages a notch 151 in a disk 152 secured on the shaft 78.

The trip or device 118 has a short arm 25 130 extending above its pivot 119, and connected to said spring 129. Extending below the pin 120, said trip has a guard portion 131 engaging the shaft 122, to prevent the trip from swinging forward to an undue 30 extent.

At Fig. 3, which is rear view, the stem 131^a of the zero key 85 has a horizontal arm 132 to engage a shoulder 133 on the error key 100; so that whenever the zero key is 35 operated all of the set pins 14 are returned to normal positions. This is an advantage, since it might otherwise happen that after setting up said pins and before operating the handle 27, the operator would inadvertently 40 operate the zero or clearance key 85, and thereby return the wheels to zero, leaving the pins depressed, and an error would hence occur in the next operation. This difficulty is avoided by coupling the keys in the manner set forth. The arm 132 does not prevent the depression of the error key 100 independently of the zero key 85.

Variations may be resorted to within the scope of the invention, and portions of the 50 improvements may be used without others.

Having thus described my invention, I claim:

1. In a combined typewriting and computing machine, the combination with a special type mounted to print on the work sheet, of a spring tending to operate said type, means restraining said type, a computing mechanism including a set of dial devices, means for returning the dial devices to zero, said 55 returning means including a key, and means associated with said key for releasing said restraining means, thereby to permit said spring to operate said special type.
2. In a combined typewriting and com-

puting machine, the combination with a special type mounted to print on the work sheet, of a spring tending to operate said type, means restraining said type, a computing mechanism including a set of dial devices, means for returning the dial devices to zero, said returning means including a key, means associated with said key for releasing said restraining means, thereby to permit said spring to operate said special type, and means associated with said computing mechanism for automatically restoring said type, spring and restraining means to normal positions.

3. In a combined typewriting and computing machine, the combination with a special type mounted to print on the work sheet, of a spring tending to operate said type, means restraining said type, a computing mechanism including a set of dial devices, means for returning the dial devices to zero, said returning means including a key, means associated with said key for releasing said restraining means, thereby to permit said spring to operate said special type, means associated with said computing mechanism for automatically restoring said type, spring and restraining means to normal positions, said zero-returning devices including a set of tens-carrying members and a shaft whereon they are mounted, and said restoring means including a cam upon said shaft, and means controlled by said cam to restore said type and its associated parts to normal positions.

4. In a combined typewriting and computing machine, the combination with a special type mounted to print on the work sheet, of a spring tending to operate said type, means restraining said type, a computing mechanism including a set of dial devices, means for returning the dial devices to zero, said returning means including a key, means associated with said key for releasing said restraining means, thereby to permit said spring to operate said special type, means associated with said computing mechanism for automatically restoring said type, spring and restraining means to normal positions, said zero-returning devices including a set of tens-carrying members and a shaft whereon they are mounted, and said restoring means including a cam upon said shaft, and means controlled by said cam to restore said type and its associated parts to normal positions, said restraining means including a trip provided with a spring to reposition it during the operation of said cam, and the latter being timed to continue in motion sufficiently to disconnect itself from the type-bar operating devices.

5. In a combined typewriting and computing machine, having a platen and types to strike thereon, the combination with a special type, of a lever connected to said type

- to operate the same, a spring tending normally to operate said lever, a trip connected to said lever to restrain the same, a clearance-key connected to the computing mechanism, and means connected to said clearance-key to release said trip. 5
6. In a combined typewriting and computing machine, having a platen and types to strike thereon, the computing mechanism including a general operator, the combination with a special type, of a lever connected to said type to operate the same, a spring tending normally to operate said lever, a trip connected to said lever to restrain the same, a clearance-key connected to the computing mechanism, means connected to said clearance-key to release said trip, and means connected to said general operator to restore said type-lever, trip and spring to normal positions. 10
7. In a combined typewriting and computing machine, having a platen and types to strike thereon, the combination with a special type, of a lever connected to said type to operate the same, a spring tending normally to operate said lever, an arm connected to said lever, a trip pivoted on said arm, a lug which is engaged by said trip, a clearance key for the computing mechanism, and means to enable said clearance key to move said lug and thereby release said trip. 15
8. In a combined typewriting and computing machine, having a platen and types to strike thereon, the combination with a special type, of a lever connected to said type to operate the same, a spring tending normally to operate said lever, an arm connected to said lever, a trip pivoted on said arm, a lug which is engaged by said trip, a clearance key for the computing mechanism, means to enable said clearance key to move said lug and thereby release said trip, and a spring to restore said trip into engagement with said lug upon the return of said lever and type to normal positions. 20
9. In a combined typewriting and computing machine, the combination with a platen and key-operated types to print thereon, of a special type, means to prevent said special type from being operated, a clearance key for the computing mechanism, and means controlled by said clearance key to effect the operation of said special type. 25
10. In a combined typewriting and computing machine, the combination with a platen and key-operated types to print thereon, of a special type, means to prevent said special type from being operated, a clearance key for the computing mechanism, means controlled by said clearance key to effect the operation of said special type, a general operator for the computing mechanism, and means to enable said general operator to restore and re-lock said type. 30
11. In a combined typewriting and computing machine, the combination with a platen and key-operated types to print thereon, of a special type, means to prevent said special type from being operated, a clearance key for the computing mechanism, means controlled by said clearance key to effect the operation of said special type, a general operator for the computing mechanism, and means to enable said general operator to restore and re-lock said type, said last named means including a shaft operated by said general operator, a cam on said shaft, and a restoring member engageable by said cam. 35
12. The combination with a computing mechanism including a zero key, of a typewriting mechanism including a special type bar, and means for enabling said zero key to cause an actuation of said type bar. 40
13. In a combined typewriting and computing machine, the combination with a platen, of key-operated types coöperating with said platen to print, a special type-bar, means to prevent said special type-bar from being operated, computing mechanism, a clearance key for said computing mechanism, means controlled by said clearance key to effect the operation of said special type-bar, a general operator for said computing mechanism, means to enable said general operator to restore and re-lock said type-bar, said computing mechanism including a shaft operated by said general operator, a cam on said shaft, and a wrist connected to said special type-bar to enable said cam to return said type-bar to normal position, said cam being constructed to clear said wrist at the end of the movement of said shaft. 45
14. The combination with a platen, of a series of type actions coöperating with said platen to print characters, a special type action for printing a special character including a type-bar, a bell crank for rocking said type-bar, and a lever for vibrating said bell crank, computing mechanism coöperating with said type actions, a zeroizing mechanism for eliminating computations exhibited by said computing mechanism, and means brought into play by said zeroizing mechanism for actuating said special type action. 50
15. The combination with a platen, of a series of type actions coöperating with said platen to print characters, a special type action for printing a special character including a type-bar, a bell crank for rocking said type-bar, a lever for vibrating said bell crank, computing mechanism coöperating with said type actions to compute numbers written by said type actions, and a zeroizing mechanism for eliminating computations exhibited by said computing mechanism, said special type action being actuated. 55

ed automatically with the actuation of said zeroizing mechanism to print a character indicating that said computing mechanism has been cleared of any computation previously exhibited.

16. The combination with a computing mechanism including a series of dial wheels arranged to exhibit a computation, of a zeroizing mechanism for clearing said computing mechanism of a computation and returning said dial wheels to zero, a platen, a series of numeral key type actions coöperating with said platen to print numbers and coöperating with said computing mechanism to compute the same numbers as printed, a special type action, a spring for actuating said special type action, and means controlled by said zeroizing mechanism for bringing said spring into play to cause said special type action to print a special character indicating that said computing mechanism has been cleared of any computation previously exhibited.

17. The combination with a platen, of a special type action coöperating with said platen to print a special character, computing mechanism including a general operator arranged to run up numbers, and a cam connected to be rotated by said general operator, coöperating with said type action to manipulate the same.

18. The combination with a platen, of a special type action coöperating with said platen to print a special character, computing mechanism including a general operator arranged to run up numbers, a cam connected to be rotated by said general operator, coöperating with said type action to manipulate the same, and locking means for determining the starting and stopping positions of said cam.

19. The combination with a platen, of a special type action coöperating with said platen to print a special character, a computing mechanism, a general operator for actuating said computing mechanism to run up numbers, a spring for operating said type action in one direction, and a gravity cam for actuating said type action in the opposite direction, said gravity cam having an abrupt dip therein to permit a sudden action of said spring.

20. The combination with a platen, of a special type action coöperating with said platen to print a special character, a computing mechanism, a general operator for actuating said computing mechanism to run up numbers, a spring for operating said type action in one direction, a gravity cam for actuating said type action in the opposite direction, said gravity cam having an abrupt dip therein to permit a sudden action of said spring, and means independent of said cam for retensioning said spring.

21. The combination with a platen, of a

series of key-operated type-bars coöperating with said platen to print, a keyless type-bar, a tensioned spring for actuating said keyless type-bar, computing mechanism coöperating with said key-operated type-bars to compute numbers, and means operated by said computing mechanism for tensioning said spring.

22. The combination with a series of computing wheels, of means, including independently operable types and keys for operating them one after another, for printing numbers shown by said wheels while the latter are stationary, whereby the written total may be compared with the number exhibited by the wheels, means for clearing said wheels to zero while said printing means is inactive, whereby the machine may be cleared without printing the number shown on the wheels, and additional printing means automatically actuated at the operation of said clearing means, to print a special character indicating only that the computing wheels have been cleared as a preliminary to performing a computation.

23. The combination of printing mechanism comprising a series of independently operable types, including a set of numeral types and a clearance-sign type, and a plurality of individual keys connected to control the operation of said types, a clearance mechanism connected to the clearance-sign key to be controlled thereby; and a computing mechanism under the control of the numeral keys, and including a register wherein totals are displayed; said clearance mechanism, said printing mechanism and said computing mechanism being independent of one another, whereby a total displayed in said register may be copied therefrom and printed upon the work-sheet for comparison with the displayed computation, while said register is stationary and before it is cleared.

24. The combination of printing means comprising a series of independently operable types, including a set of numeral types and a clearance-sign type, and a plurality of individual keys connected to control the operation of said types, a step-by-step feeding carriage under the control of the numeral keys to enable numbers to be printed digit by digit, a clearance mechanism connected to the clearance-sign key to be controlled thereby; and a computing mechanism under the control of the numeral keys, and including a register wherein totals are displayed; said printing means, said clearance mechanism and said computing mechanism being independent of one another, whereby a total displayed in said register may be copied therefrom and printed upon the work-sheet for comparison with the displayed computation, while said register is stationary and before it is cleared.

25. The combination of a series of inde-

pendently operable types, including a clearance-sign type, a plurality of individual keys connected to control the operation of said types, a clearance mechanism connected to the clearance-sign key to be controlled thereby; said types including a set of numeral types; and a computing mechanism under the control of the numeral keys; means being provided for printing said clearance-sign type in or out of the adding column at will.

26. The combination of a series of computing wheels, means operable independently of the wheels for printing the numbers shown by said wheels, said printing means including numeral types operable independently of one another and individual keys for operating them, mechanism operable independently of said printing means for turning said wheels to zero, and an additional printing mechanism under the control of said zero mechanism, for printing a clearance sign, whereby after printing a total by the manipulation of said keys, the total may be left upon the wheels for comparison with the total printed on the sheet, and whereby the wheels may thereafter be cleared independently of said number-printing mechanism, and a sign also printed to indicate that the wheels are cleared before starting a fresh computation.

27. The combination with printing means, inclusive of a carriage, whereby numbers may be printed in any one of a large number of columns side by side on a work-sheet, of computing means whereby numbers printed in certain of said columns may be computed, said computing means including a register wherein totals are displayed, a key, means connected to said key to clear said computing means, and a printing type connected to said clearance means and printable in any of said columns where said numbers are printed; said clearance means, said printing means and said computing means being independent of one another, whereby a total displayed in said register may be copied therefrom and printed on the work-sheet, while the register is stationary and before said clearance means is actuated, so as to enable the registered and printed totals to be compared.

28. The combination with a series of computing wheels, of digit-printing means for printing the numbers as computed and run into said computing wheels, zeroizing means for clearing said computing wheels of a computation registered therein, said zeroizing means and said digit-printing means constructed for alternative action, so that each is necessarily silent while the other is in action, whereby a total may be left upon the computing wheels for comparison with the computation printed on the work-sheet, and whereby said wheels

may thereafter be cleared independently of said digit-printing means, and printing means incited to action by said zeroizing means, to print a sign characteristic of the zeroizing operation.

29. The combination with computing mechanism including a series of computing wheels, of printing mechanism for printing digit by digit the numbers computed and run into said computing wheels, said printing mechanism comprising individual printing elements corresponding to the several digits and having the same printing point or point of strike so as to be operable singly, zeroizing means for clearing said computing wheels to zero, and a printing element caused to act by said zeroizing means to print a characteristic sign; said last-mentioned printing element having the same printing point or point of strike as said first-mentioned printing elements.

30. The combination with computing mechanism including a series of computing wheels, of printing mechanism for printing digit by digit the numbers computed and run into said computing wheels, said printing mechanism comprising individual printing elements corresponding to the several digits and having the same printing point or point of strike so as to be operable singly, zeroizing means for clearing said computing wheels to zero, and a printing element caused to act by said zeroizing means to print a characteristic sign; said last-mentioned printing element having the same printing point or point of strike as said first-mentioned printing elements, said zeroizing means and said first-mentioned printing mechanism being alternative in their action so that said last-mentioned printing element will print at a different time from printing actions of said first-mentioned printing elements.

31. The combination of a series of keys, types operable one after another by said keys, a series of computing wheels under the control of said keys, means for clearing said wheels to zero, and printing means independent of said keys and automatically actuated at the operation of said clearing means, to print a special character indicating that the computing wheels have been cleared.

32. The combination with a computing mechanism including a series of numeral keys and also including a register wherein totals are displayed, of printing mechanism including numeral types operable by said keys, and automatic means brought into play by said computing mechanism independently of said keys for causing the printing of a special character indicating a certain state of said computing mechanism; said printing mechanism and said computing mechanism being independent of each other, whereby a total displayed in said

- register may be copied therefrom and printed on the work-sheet, while the register is stationary, so as to enable the registered and printed totals to be compared.
33. The combination with a computing mechanism including a set of numeral keys and a register, of printing means including numeral types operable by said keys and also including zero clearing means, means for printing a special character, means normally tending to actuate said special printing means, a trip preventing the actuation of said special printing means, and means actuated by said zero clearing means for releasing said trip; said zero clearing means, said computing mechanism and said printing means being independent of one another, whereby a total displayed in said register may be copied therefrom and printed on the work-sheet, while the register and the zero clearing means are stationary, so as to enable the registered and printed totals to be compared.
34. The combination with printing means comprising a series of numeral keys and a series of numeral types operable thereby, of a computing mechanism controllable by said keys and including a register and a general operator for running up on said register a previously set-up computation, independent means for printing a special character to indicate a certain state of said computing mechanism, a spring normally tending to actuate said independent printing means, and means actuated by said general operator for tensioning said spring; said computing mechanism and the first-named printing means being independent of each other, whereby a total displayed in said register may be copied therefrom and printed on the work-sheet, while the register is stationary, so as to enable the registered and printed totals to be compared.
35. The combination with printing means comprising a series of keys and a series of types operable thereby, of a computing mechanism including indexing devices controllable by said keys and also including a register and a general operator for running up on said register the number indexed, a device independent of said keys for printing a special character to indicate a certain state of said computing mechanism, and means controlled by said general operator for returning said independent printing device to normal position; said computing mechanism and the first-named printing means being independent of each other, whereby a total displayed in said register may be copied therefrom and printed on the work-sheet, while the register is stationary, so as to enable the registered and printed totals to be compared.
